UNITED STATES PATENT OFFICE.

NORMAN BLY, OF CROWNPOINT, NEW YORK.

CUTTER-HEAD.

SPECIFICATION forming part of Letters Patent No. 696,794, dated April 1, 1902.

Application filed September 20, 1901. Serial No. 75,692. (No model.)

To all whom it may concern:

Be it known that I, NORMAN BLY, a citizen of the United States, and a resident of Crown-point, in the county of Essex and State of New York, have invented a new and Improved Cutter-Head, of which the following is a full, clear, and exact description.

The invention relates to woodworking-tools; and its object is to provide a new and improved cutter or matcher-head which is simple and durable in construction and arranged to permit convenient and quick adjustment of the knives for forming tongues and grooves or for dressing the sides of heavy material and to prevent breaking of the edges of the material in front of the knives, thus insuring a clean cut and considerable saving of lumber.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement on the line 1 1 in Fig. 2. Fig. 2 is a plan view of the same, and Fig. 3 is a sectional plan view of the same on the line 3 3 of Fig. 1.

On the spindle or mandrel A of a wood-working-machine is fitted to slide vertically a sleeve-like carrier B, adapted to be adjusted in a vertical direction by a set-screw C and arranged to be securely fastened in place on the spindle after adjustment is made by a set-screw C'. On the carrier B are removably held the cutter-blocks D D' and the circular saw E, located between the blocks D D' and clamped with the same in position on the carrier B between an integral flange B' and a nut B'', screwing on the threaded portion B''' of the said carrier. The cutter-blocks D D' are alike in construction, and each is formed with radial guideways, in which are mounted to slide cutter-bars F, secured in place by bolts G and carrying segmental knives H, each cutter-bar F being provided with a peripheral guideway F', engaging a groove in the under side of the corresponding knife H, the said groove being also engaged by the head I' of

a bolt I, extending through the cutter-bar F, to securely fasten the knife H in place after the same has been segmentally adjusted on the guideway F'. Each cutter-block D and D' is also formed with another set of radial guideways for the cutter-blocks F² to slide in, and on the outer ends of the cutter-blocks F² are adjustably secured straight knives J by means of bolts I², as plainly illustrated in the drawings. The cutter-bars F² are secured in place after the desired adjustment is made by clamping-bolts G', similar to the bolts G above referred to. Chip-breakers K are secured by bolts K' to the sides of the cutter-bars F F², and the outer ends of the said chip-breakers K are formed with bevels for engaging the bevels of the knives H and J, the said chip-breakers preventing the usual breaking of the edges in front of the knives, thus saving lumber and at the same time forming a self-set for the knives to enable the operator to properly set the knives in position on the cutter-bars. It is understood that the knives H and J alternate, and by adjusting their cutter-bars F and F² on the cutter-blocks any desired cut can be made to properly trim or dress the lumber to the size of the groove cut by the circular saw E.

Having thus described my invention, I claim as new and desire to secure by Letters Patent—

1. A cutter-head, comprising cutter-blocks, knives on said cutter-blocks, chip-breakers carried by the cutter-blocks and having beveled outer ends to engage the bevels of the knives, a circular saw between the cutter-blocks, and a carrier for attachment to a spindle or mandrel and removably supporting the said blocks and saw, the said carrier having means for clamping the blocks and saw together and holding the same in position on the carrier, as set forth.

2. A cutter-head having cutter-bars arranged in sets, segmental knives held adjustably on the outer ends of one set of cutter-bars, straight knives held adjustably on the outer ends of the other set of cutter-bars, and a chip-breaker for each knife having a beveled edge to engage the bevel of the knife, as set forth.

3. A cutter-head, comprising a cutter-block having two sets of radial guideways, sets of

5 cutter-bars slidably secured in the said guideways each cutter-bar having a guideway at its outer end, segmental knives adjustably secured on the guideways of one set of cutter-bars, straight knives secured on the guideways of the other set of cutter-bars, and chip-breakers secured to the cutter-bars and having their outer ends beveled, as set forth.

10 4. A cutter-head having a cutter-bar, a knife held on said cutter-bar, and a chip-breaker adjustably secured on the cutter-bar and having a beveled outer end to engage the bevel of the knife, as set forth.

15 5. A cutter-head, having a knife, and a chip-arrester and knife-setter engaging the bevel of the knife, as set forth.

20 6. A cutter-head, comprising a cutter-block having radial guideways, cutter-bars slidably secured in the said guideways, each cutter-bar having a peripheral guideway at its outer end and a segmental knife adjustably secured on the guideway of the said cutter-bar, and a chip-breaker adjustably secured on the side of the cutter-bar to engage the bevel of the 25 corresponding knife, as set forth.

7. A cutter-head, comprising a cutter-block having radial guideways, cutter-bars slidably secured in the said guideways, each cutter-bar having a peripheral guideway at its outer

end and a segmental knife adjustably secured 30 on the guideway of the said cutter-bar, and a chip-breaker adjustably secured on the side of the cutter-bar to engage the bevel of the corresponding knife, the said chip-breaker having a beveled outer end for engaging the 35 bevel of the knife, as set forth.

8. A cutter-head, comprising cutter-blocks, cutter-bars adjustable on the cutter-blocks and formed with guideways, segmental and straight knives arranged alternately on said 40 guideways and fitted to slide thereon, means for securing the knives in place on the cutter-bars after adjustment, chip-breakers adjustably secured to the sides of the cutter-bars and having their outer ends beveled to 45 engage the bevels of the said knives, a saw between the cutter-blocks and a carrier for attachment to a revoluble spindle and removably supporting the said cutter-blocks and saw, as set forth. 50

In testimony whereof I have signed my name to this specification in the presence of two witnesses.

NORMAN BLY.
